UNITED STATES PATENT OFFICE.

CLEMENT G. HARRINGTON, OF MAPLEWOOD, MISSOURI, ASSIGNOR TO
WOLFF TRUCK FRAME COMPANY, OF AUGUSTA, MAINE, A CORPO-
RATION OF MAINE.

CAR-TRUCK.

No. 857,937.

Specification of Letters Patent.

Patented June 25, 1907.

Application filed April 27, 1907. Serial No. 370,659.

To all whom it may concern:

Be it known that I, CLEMENT G. HARRINGTON, a citizen of the United States, residing at Maplewood, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a side elevational view of a car truck showing a side frame constructed in accordance with my invention; Fig. 2 is a cross sectional view of the side frame; and Fig. 3 is a perspective view showing a bolster which is intended to be used with my improved side frame.

This invention relates to car trucks, and particularly to that type in which the side frames consist of a one-piece casting.

The main object of my invention is to provide a cast metal side frame which is so constructed that it permits the use of a bolster of standard type, and enables the bolster to be put in place and removed easily.

Another object is to provide a cast side frame provided with an opening to receive the end of a bolster, said opening being so formed that the bolster can be inserted in a vertical position and thereafter rotated in a horizontal position and moved upwardly so that its column guides will embrace the columns of the side frame.

The standard bolster which is now in general use, is provided on its sides with integral laterally projecting column guides, and between said guides the side faces of the bolster are perfectly flat so as to provide an extended bearing surface between the bolster and the columns of the side frames of the truck. The distance between the inside faces of the columns must correspond to the width of that portion of the bolster which lies between the columns, and as the column guides project laterally beyond the sides of the bolster the only way in which the bolster can be inserted in a one-piece side frame is to arrange it first in a vertical position between the columns and then turn it into a horizontal position so that its column guides will embrace the columns of the side frames. My improved side frame is so formed that this rotating or turning of a standard type bol-

ster is permitted in placing it in an operative position.

Referring to the drawings which illustrate the preferred form of my invention, 1 designates one of the side frames of a car truck. This side frame consists of a one-piece casting, preferably of steel, and provided with an opening 2 of sufficient depth to receive the end of the bolster 3 when it is arranged in a vertical position. The columns 4 which form the sides of said opening are provided on their inner sides with integral flanges 5, and the distance between the upper ends of these columns at the point where the bolster is located when in operative position, corresponds to the width of the bolster so that the sides of the bolster will bear firmly against the inside flanges of the columns.

At approximately the middles of the columns are curved portions 6, the distance between the curved portions of the two columns being greater than the distance between the upper ends of the columns so that the bolster can be turned from a vertical position into a horizontal position and then moved upwardly to cause its integral column guides 7 to embrace the columns of the side frames.

The side frames of the truck are connected together by a "spring plank" which preferably consists of two angles 8 that project beyond the side frames, as shown in Fig. 2, and form seats for the coiled springs 9 upon which the bolster rests, the side frames also being provided with lateral projections 10 that are arranged between the angles 8 to form parts of the spring seats.

Having thus described my invention, what I claim as new and desire to secure by Letters Patent is:

1. A car truck side frame provided with an opening to receive the end of a bolster having integral column guides, said frame comprising columns which have curved portions intermediate their ends that permit the bolster to be turned from a vertical into a horizontal position; substantially as described.
2. A car truck side frame consisting of a casting that is provided with an opening to receive the end of a bolster, and columns forming the sides of said opening and provided at approximately their centers with curved portions; substantially as described.
3. A car truck side frame consisting of a

casting having an opening to receive the end of a bolster, portions of the side walls of said opening being curved to permit the bolster to be turned from a vertical into a horizontal 5 position; substantially as described.

4. A car truck side frame consisting of a one-piece casting that is provided with an opening to receive the end of a bolster and with flanges forming the side walls of said 10 opening, said side walls having curved portions that permit the bolster to be turned from a vertical into a horizontal position; substantially as described.

5. In a car truck, a side frame provided 15 with an opening to receive the end of a bolster, said opening being so formed that the bolster can be inserted in a vertical position and thereafter turned into a horizontal position, and a bolster arranged in said opening 20 and provided with laterally projecting column guides and flat side faces between said guides; substantially as described.

6. In a car truck, a side frame provided with an opening to receive the end of a bolster, and a bolster arranged in said opening 25 and provided with laterally projecting column guides, a portion of said opening corresponding to the width of said bolster, and a portion of said opening being of greater 30 width than the bolster to permit it to be turned from a vertical into a horizontal position; substantially as described.

7. In a car truck, a side frame comprising a casting that is provided with an opening to 35 receive the end of a bolster, and a bolster arranged in said opening and provided with laterally projecting column guides, portions of the side walls of said opening being curved to permit the bolster to be turned from a 40 vertical into a horizontal position; substantially as described.

8. In a car truck, a side frame comprising a casting provided with columns having curved portions, a bolster arranged between 45 said columns above the curved portions thereof, and guides on said bolster which embrace the columns of the side frames; substantially as described.

9. In a car truck, a side frame having columns provided on their inner sides with flanges, said columns having curved portions

intermediate their ends, and a bolster arranged between said columns and provided with laterally projecting column guides that embrace the columns of the side frames and 55 flat side faces that bear against the flanges on the insides of said columns; substantially as described.

10. In a car truck, a side frame provided with an opening to receive the end of a bolster and flanges forming the sides of said opening, and a bolster provided with column guides and with flat side faces between said guides, said bolster being adapted to be inserted edgewise in the opening in the side 60 frame, and thereafter turned to cause its column guides to embrace the flanges on the side frame; substantially as described.

11. In a car truck, side frames provided with openings to receive the ends of a bolster and flanges forming the sides of said openings, a bolster provided with column guides and with flat faces between said guides, said bolster being adapted to be inserted edge- 70 wise in the openings in the side frames and thereafter turned to cause its column guides to embrace the flanges on the side frames, a spring plank, and springs interposed between the spring plank and the bolster; substantially as described. 80

12. In a car truck, side frames provided with openings to receive the ends of a bolster and flanges forming the sides of said openings, a bolster provided with column guides and with flat faces between said guides, said 85 bolster being adapted to be inserted edge- wise in the openings in the side frames and thereafter turned to cause its column guides to embrace the flanges on the side frames, a spring plank consisting of two angles that 90 are connected to the side frames and project beyond said frames to form spring seats, and coiled springs interposed between said spring seats and the end portions of the bolster; substantially as described. 95

In testimony whereof I hereunto affix my signature in the presence of two witnesses, this twenty fourth day of April 1907.

CLEMENT G. HARRINGTON.
